(57) **CLAIM**

The ornamental design for a treadmill as shown and described.

DESCRIPTION

FIG. 1 is a front, upper, right perspective view of a treadmill of our new design in a first configuration;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an enlarged view of the area labeled 8 in FIG. 2; and

FIG. 9 is an enlarged view of the area labeled 9 in FIG. 1.

FIG. 10 is a front, upper, right perspective view of the treadmill in a closed configuration;

FIG. 11 is a front view thereof;

FIG. 12 is a rear view thereof;

FIG. 13 is a left view thereof;

FIG. 14 is a right view thereof;

FIG. 15 is a top view thereof; and,

FIG. 16 is a bottom view thereof.

The dash-dash lines of the drawings illustrate portions of the treadmill that form no part of the claimed design.

1 Claim, 16 Drawing Sheets
